Attorney

UNITED STATES PATENT OFFICE.

THEODORE BIRKENMAIER, OF ST. LOUIS, MISSOURI, ASSIGNOR TO W. N. MATTHEWS
CORPORATION, OF ST. LOUIS, MISSOURI, A CORPORATION OF MISSOURI.

DISCONNECTING BLOCK.

Application filed August 9, 1926, Serial No. 128,082. Renewed August 17, 1928.

This invention relates to disconnecting blocks and with regard to certain more specific features to a disconnecting hinge block for fuses, switches and the like.

5 Among the several objects of the invention
may be noted the provision of a disconnecting
hinge block which is adapted to permit safe,
fast and positive manipulation thereof in re-
mote and inaccessible positions of said block
10 and in precarious positions of the operator
thereof; and the provision of a device of the
class described which is relatively simple and
inexpensive in manufacture. Other objects
will be in part obvious and in part pointed
15 out hereinafter.

The invention accordingly comprises the elements and combinations of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a side elevation showing the improved hinge block applied to a fuse cartridge and in position on an insulating hanger;

Fig. 2 is an enlarged side elevation of the block portion showing certain alternate positions of elements thereof;

Fig. 3 is a left side elevation of Fig. 2;

Fig. 4 is a bottom plan view of Fig. 2;

Fig. 5 is a perspective view of a terminal piece; It consists of a base 10, a central vertical support 11, and a horizontal top plate 12.

Fig. 6 is a side elevation of the hinge block assembly in normal connected position; Fig. 7 is a side elevation similar to Fig. 6 showing

Fig. 7 is a view similar to Fig. 6 showing in solid lines an abnormal connected position, and in dotted lines an alternate disconnected position; and,

Fig. 8 is a left side elevation of the hinge element shown in Fig. 7.

Similar reference characters indicate corresponding parts throughout the several views of the drawings.

Referring now more particularly to Fig. 1 of the accompanying drawings, there is illustrated at numeral 1 a conventional cross arm adapted to support an insulator bracket 3. The insulators 5 of the bracket 3 support arms 7 which have bolted thereto pairs of terminal spring clips 9. These clips are of the class which engage two sides of a connecting

member by means of a plurality of spring 55 engaging fingers.

Bolted between each set of clips 9 and its respective arm 7 is a terminal piece 11 (see Figs. 1 and 5). Each piece 11 is provided with outwardly bent ears 13. These ears have openings 15 therein for the purpose of receiving connecting bolts, whereby one or more leads may be fastened to the each terminal piece. 60

Between the lowermost terminal piece 11 and its respective arm 7 is held a hinge member 17. This member 17 is provided with flanges 19 for the purpose of engaging the substantially straight sides of the arm 7, thereby retaining said hinge member 17 in the predetermined position shown in the drawings. 70

The hinge member or hinge 17 has a flat portion 21 adapted to flatly engage said arm 7. This portion has a proper opening therein for permitting passage of the bolt which holds the arm 7, hinge 17, terminal 11 and clip 9 together. Reference to Fig. 5 shows that the terminal piece 11 also has such an opening. The hinge also comprises a pair of downwardly hooked arms 23 and a lip 25 extending from said flat portion 21 and between said hooked arms 23. 75 80

A fuse cartridge 27 carries a fuse 29 which is adapted to electrically connect the spring terminal clips 9. This fuse is removably connected to an upper metallic block 31 which is provided with proper parallel faces for engaging the resilient spring clips 9. A stud 33 removably retains the fuse in position with said upper block 31. This block is also provided with a suitable bridge portion 35 which may be hooked by the end of a suitable insulating tool 37, so that an operator may draw the block 31 from the upper clip 9 without physically engaging current carrying members. 85 90 95

The di-electric cartridge 27 is held to the block member 33 by a suitable set screw and is fastened in a like manner to a lower improved form of hollow terminal hinge block 39. This block 39 comprises a hollow malleable casting having substantially flat parallel faces 41 for the purpose of engaging the resilient spring clips 9. Below and with the faces 41 is formed a body portion 43 from which extend sideward, gudgeons 45 for the purpose of hingedly engaging the hinge member 17 at the hooked portions of the arms 23.

On one face of the body 43 is provided a

tapped surface adapted to receive a set screw 46 for holding the lower end of said fuse 29. The fuse passes from the hollow interior of the cartridge 27, through the hollow body 23, 5 between two lugs 47, and is forked under the head of said screw 45, whereby it may be connected. The lugs also serve other purposes hereinafter to be described.

I order to prevent the set screw from coming completely out of its screw hole when unfastened, a spur 49 is cast with the body 43, in the position shown by dotted lines in Fig. 2. After the set screw is applied to the screw hole, the spur 49 is put into its solid line position by striking it a blow, whereupon it limits the travel of the set screw 46. Hence the screw may be unfastened but it is impossible to unscrew it to such an extent that it will drop to the ground. This is of great advantage where a line man, in renewing a fuse, is working at more or less great heights in precarious positions such as in high winds or the like. The line man needs not consider the exact amount to which he is unscrewing the 25 set screw as its travel is automatically limited.

Substantially opposite the screw 45 and on the body 43 is provided a nose or lug 51 below which is formed a toe 53, said nose 51 and toe 53 having a notched space 55 left 30 therebetween. The said lugs 47 which are formed oppositely to the toe 53, it may be noted, have no corresponding space such as 55 left above them. This particular arrangement of elements is provided for several reasons, which are as follows:

Heretofore when line men applied their tools 37 to the bridge member 35 and drew down the upper block 33 to disconnect the fuse, the purpose was to swing the fuse down 40 whereupon it would theoretically be left hanging with the gudgeons 45 in the curved portions of the arms 23. It has been found however, that under certain conditions of tightness at the lower spring clips 9, the fuse cartridge 45 would tend to pivot at said clips such as at a point X (see Figs. 6 and 7). This was especially true where the cartridges were not vertically mounted and where the pull required in opening the device did not supply enough 50 component of force to positively put the gudgeons in position at the curved portions of the arms 23. Hence, under certain circumstances, such as after the blowing of a fuse when the cartridge had been raised to a 55 position at or near the solid line position shown in Fig. 7, the downward swing with the pivot point at X resulted in the gudgeons 45 swinging out from the curved portions of the arms 23 as illustrated by the arrow in Fig. 6. The result was that as soon as both sets of 60 clips 9 had been cleared by the blocks 33 and 39, the cartridge would fall to the ground doing injury to the cartridge, or perhaps bystanders below. The line man was also forced 65 to climb down and retrieve the cartridge.

The described conditions were aggravated where cartridges were positioned horizontally because no component of the opening pull was available for seating the gudgeons 45 into the curved portions of said arms 23.

Another difficulty heretofore experienced has been that line men, when in difficult positions and not apt to watch small details, attempted to reverse the position of a cartridge in placing it. This has often resulted in 75 breakage, because after the gudgeons have been placed in the arms 23 the cartridge is usually given a sudden push in order to properly seat the blocks in the clips.

The arrangement of parts as hereinbefore described overcomes these difficulties. First, the upper arcuate edge 57 of the nose 51 is adapted to engage the lip 25 (if the fuse is raised such as when blown). This means that although the gudgeons 45 are raised to 85 such a position that they might ordinarily leave the curved portion of the arms 23, they will never do so, because pivoting about the point of friction X is substantially prevented by the cooperation of nose 51 with the lip 25. 90 The result is that as the cartridge is being rotated to disconnect the body portion 43 or pulled down by the method shown in Fig. 1, that is, from its solid line position in Fig. 7 to its dotted line position in Fig. 7, the gudgeons will always remain within the compass 95 of the curved portions of the arms 23. Hence as the cartridge is permitted to swing downwardly under action of gravity it will always remain suspended from the hinge member 17. 100

At the same time this particular construction forces the operator to apply the cartridge in its correct position. This is by reason of the fact that the only way in which to bring the gudgeons 45 into a position whereby they may pass through the opening Y of the arms 23 is to bring the notch or recess 55 into cooperation with the lip 25 while the cartridge is held more or less at a substantial angle with respect to the general direction of the arms 25. The gudgeons may then be drawn 110 forwardly and sunk into the curved portions of the arms 23 by way of said openings Y (see dotted lines Fig. 7). It is evident that if the cartridge is inadvertently turned upside down 115 that no notch (similar to notch 55) is available above the lugs 47 for permitting cooperation with the lip 25. The result is that the gudgeons 45 cannot be brought high enough 120 to enter the passage Y. The operator is never permitted to hook in his cartridge in a wrong position after which he might be apt to break it if the mistake were not realized. With the present construction the cartridge 125 cannot be broken by this means. The purpose of the toe 53 is engagement thereof with the lip 25 as the cartridge swings down whereby said cartridge is held in a predetermined position for working thereon, rather than being permitted to swing or oscillate under gravi- 130

tational action, as has heretofore been the case.

It is evident from the above that this invention provides a hinge block which is absolutely proof against the ordinary contingencies which have heretofore made the installation of fuse cartridges an expensive and time-consuming operation. This is done by improvements in a single casting and other simple cooperating features. It is to be understood that the improvements herein set forth may also be used with switch bars or like connecting members between the blocks 33 and 39 instead of the described fuse connecting member.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. A disconnecting block assembly for fuses, switches and the like comprising a hinge member, a body portion for holding a connecting member adapted to electrically cooperate with terminal clips, gudgeons on said body portion adapted to hingedly support said body portion in the hinge member, means for applying and removing the gudgeons of the body portion to and from the hinge member, and means for positively preventing a disconnection between the hinge member and the gudgeoned body portion when said body portion is being rotated to disconnect from said clips, said last-named means comprising a lug on said body portion adapted to cooperate with an element of the hinge member, whereby substantial relative rotation of the body portion at said clips is prevented.

2. A disconnecting block assembly for fuses, switches and the like comprising a hinge member, a body portion for holding a connecting member adapted to electrically cooperate with terminal clips, gudgeons on

said body portion adapted to hingedly support said body portion in the hinge member, means for applying and removing the gudgeons of the body portion to and from the hinge member, and means for positively preventing a disconnection between the hinge member and the gudgeoned body portion when said body portion is being rotated to disconnect from said clips, said last-named means comprising a lug on said body portion adapted to cooperate with an element of the hinge member, whereby substantial relative rotation of the body portion at said clips is prevented, means for permitting some, but limited, rotation of the body portion at its gudgeons on the hinge member, said last-named means also being adapted to require a predetermined proper application of the body portion to the hinge member.

3. A disconnecting assembly comprising a hinge member, a body portion adapted to cooperate with terminal clips, means for hingedly and removably supporting the body portion on the hinging member, and means for positively preventing disconnection between the hinge member and body portion when said body is being rotated to disconnect from said clips, said last-named means being adapted to prevent substantial relative rotation of the body portion with respect to the hinge portion at said clips.

4. A disconnecting assembly comprising a hinge member, a body portion adapted to cooperate with terminal clips, means for hingedly and removably supporting the body portion on the hinging member, and means for positively preventing disconnection between the hinge member and body portion when said body is being rotated to disconnect from said clips, means on the body for holding a circuit closing member, and means for limiting the movement of said holding means to prevent inadvertent dropping thereof, whereby said assembly is made completely safe for manipulation.

In testimony whereof, I have signed my name to this specification this 6th day of August, 1926.

THEODORE BIRKENMAIER.
